ATTORNEY.

UNITED STATES PATENT OFFICE

JOHN CLARK, OF WALKERTON, INDIANA

TIE TAMPER

Application filed October 17, 1929. Serial No. 400,340.

My invention relates to a tamping device for use in connection with railway ties, for forcing the ballast beneath the ties.

An important object of the invention is to provide a device of the above mentioned character which is self-adjusting when used in connection with ties of different vertical thicknesses, whereby the ballast may be properly forced beneath such ties without necessity of adjusting parts of the device.

A further object of the invention is to provide a device of the above mentioned character, which is extremely simple in construction, strong and durable.

Other objects and advantages of the invention will be apparent during the course of the following description.

In the accompanying drawings, forming a part of this specification, and in which like numerals are employed to designate like parts throughout the same,

Figure 1 is a perspective view of a tamping device embodying my invention, showing the same in use,

Figure 2 is an end elevation of the same, and,

Figure 3 is a side elevation of the device, as viewed from the line 3—3 of Figure 2.

In the drawings, wherein for the purpose of illustration, is shown a preferred embodiment of my invention, the numeral 5 designates a track rail arranged upon cross ties 6, having ballast 7, to be tamped under the cross ties.

The tamping device embodies a brace arm or bar 8, provided with a clamp for detachable engagement with the base flange 9 of the rail 5. This clamp embodies a straight vertical jaw 10, preferably bent from the end of

the arm or bar 8, and a generally horizontal jaw 11, arranged upon the top of the arm or bar 8 and secured thereto by rivets 12, or the like.

The upper horizontal jaw 11 has a screw-threaded opening for receiving a clamping bolt 13, to engage with the top of the base flange 9. The brace arm or bar 8 is provided at its outer end with a loop-handle 14, rigidly attached thereto, and extending transversely of the same. It is thus seen that

the brace arm or bar 8 is passed under the

base flange 9 and clamped thereto and will extend between adjacent cross ties 6, in parallel relation to the same.

I provide a tamping element which is designated as a whole by the numeral 15. This tamping element embodies a preferably straight handle 16 having a transverse grip 17. The handle 16 is provided at its lower end with an inclined portion 18, disposed at an obtuse angle with relation thereto. Formed integral with the inclined portion 18 is a curved cam portion 19 which has its convex side extending in an opposite direction to the inclined portion 18. A tamping head 20 is formed integral with the lower end of the curved cam portion 19, as shown.

In use, the brace arm or bar 8 is clamped or secured to the base flange 9 at the desired point from the cross tie 6, beneath which it is desired to tamp the ballast.

The tamping element 15 is now inserted between such cross tie and the brace arm or bar 8, and its curved cam portion engages or rests against the arm or bar 8. By a vertical and swinging movement of the tamping element, the ballast 7 may be worked beneath the selected cross tie 6. It frequently happens that cross ties vary in vertical thickness, anywhere from six to ten inches. When this occurs, it is unnecessary to change the adjustment of the brace arm or bar 8 upon the base flange, as the cam portion 19 will permit of the manipulation of the tamping element to properly tamp the ballast beneath cross ties of various vertical thicknesses, which is rendered possible by having the curved cam portion of a length whereby it will function in connection with cross ties having the maximum varying vertical thicknesses.

It is to be understood that the form of my invention, herewith shown and described, is to be taken as a preferred example of the same, and that various changes in the shape, size and arrangement of parts, may be resorted to without departing from the spirit of my invention, or the scope of the subjoined claims.

Having thus described my invention, I claim:

1. A tamping device for forcing ballast un-

der railway ties, comprising a brace arm, means to adjustably attach the brace arm to a rail so that the brace arm will extend longitudinally of the cross tie, and a tamping element having a relatively long curved cam portion to engage with the edge of the brace arm, said curved cam portion being longitudinally adjustable of the brace arm, said cam portion carrying a tamping head, the 10 length of the cam portion permitting the tamping element to be used in tamping ballast under cross ties having varying vertical thicknesses.

2. A tamping device for forcing ballast under railway ties, comprising a brace arm, means to adjustably attach the brace arm to a rail so that the brace arm will extend longitudinally of the cross tie, and a tamping element having an inclined portion and a relatively long curved cam portion, the convex side of the curved cam portion extending in an opposite direction to the inclined portion, said curved cam portion contacting with the edge of the brace arm and adjustable longitudinally of the same, said curved cam portion having a tamping element at its free end, the length of the cam portion permitting the device to be used in tamping ballast under cross ties having varying vertical thicknesses.

3. A tamping device for forcing ballast under railway ties, comprising a brace arm, clamping means carried by one end of the brace arm to adjustably engage with the base flange of the rail, a handle secured to the opposite end of the brace arm, and a tamping element for co-action with the brace arm, including a handle having an inclined portion and a curved cam portion carried by the inclined portion, said curved cam portion engaging the edge of the brace arm and longitudinally adjustable of the same.

In testimony whereof I affix my signature.
JOHN CLARK.
